UNITED STATES PATENT OFFICE.

HURSHEL R. COFFMAN, OF KANSAS CITY, MISSOURI.

FLYING-MACHINE.

1,077,258.

Specification of Letters Patent.

Patented Nov. 4, 1913.

Application filed February 12, 1912. Serial No. 677,100.

To all whom it may concern:

Be it known that I, HURSHEL R. COFFMAN, a citizen of the United States, and a resident of Kansas City, in the county of Jackson and State of Missouri, have invented certain new and useful Improvements in Flying-Machines, of which the following is a specification.

My invention relates to improvements in flying machines.

One object of my invention is to provide a construction which will retain its equilibrium, and which will not require flexing of the planes or similar contrivances for preventing lateral tipping or swaying of the machine.

A further object of my invention is to provide a front plane guiding mechanism which will automatically tend to retain the front guiding plane in the proper inclined position suitable to keep the machine on an even keel while it is moving horizontally.

Still another object of my invention is to provide a frame which will be strong and which will not yield under the weight of the operator and engine, should the machine on striking the ground be tipped forwardly so as to alight only on the forward carrying wheel.

My invention provides further a novel form of carriage frame which will have great resistance to strains applied in any direction against the carrying wheels.

Other novel features of my invention are hereinafter fully described and claimed.

In the accompanying drawings which illustrate the preferred form of my invention, Figure 1 is a side elevation of the machine. Fig. 2 is a horizontal section on the line *a*—*b* of Fig. 1. Fig. 3 is a cross section on the line *c*—*d* of Fig. 1. Fig. 4 is an enlarged vertical sectional view on the line *e*—*f* of Fig. 1.

Similar reference characters designate similar parts in the different views.

The frame of the machine preferably includes vertical standards 1 to which are secured horizontal concave-convex supporting planes 2 and 3 disposed one above the other with their concave sides down, the planes being disposed centrally with respect to the machine. By reason of the planes being arranged as described, and by reason of the center of gravity of the machine being located below the lower plane 3 and centrally with respect to the width and length of the

planes 2 and 3, the machine is not liable to lateral tipping, but will preserve an even keel, even when the engine stops. For this reason the planes 2 and 3 may be relatively rigid and stationary, as no flexing thereof is required to preserve lateral equilibrium.

The base of the frame consisting of horizontal longitudinal bars 4 and cross bars 5 is supported by brace rods 6 upon a diamond shaped carriage frame comprising four bars 7 having their ends secured to bearing members 8 in which are respectively rotatively mounted four carrying wheels 9. The diamond shaped carrying frame is disposed with its greatest dimension in alignment with the longitudinal center of the machine, one wheel 9 being disposed at each corner of the diamond. With this arrangement the carrying frame has great strength to resist strains applied to it in any direction.

10 designates the engine, the base of which is supported by cross bars 11 of the frame. Preferably the engine 10 is located centrally with respect to the width and length of the plane 3.

12 is the propeller shaft of the engine, said shaft extending, preferably horizontally rearwardly and having secured to it the propeller 13.

Two parallel brace rods 14 have their forward ends secured to the forward bearing members 8 and extend upwardly and rearwardly and have their rear ends secured to the base of the engine 10. A lever comprising a vertical tube 15 with its upper end secured to the horizontal portion of a U shaped bar 16 is pivoted to a horizontal bar 17 the ends of which extend through and are secured respectively to the brace rods 14 at a point forward of the engine 10. Secured to the brace rods 14 between the lever just described and the engine 10 is a seat 18 for supporting the operator of the machine.

The frame of the machine is provided at its forward end with two pairs of forwardly extending bars 19 the rear ends of which are secured to the forward standards 1. The forward ends of the bars 19 of each pair are secured to a bearing member 20. Pivoted in the bearing members 20 is a horizontal rock shaft 21 to which is secured at its middle a guiding plane 22. Secured to the rock shaft, preferably by set screws 23, at opposite ends of the plane 22 are downwardly extending cranks 24 which are circumferentially adjustable on the rock

shaft 21 so that the proper inclination may be given to the plane 22 when the cranks 24 are vertically disposed. A connecting rod 25 has its forward end bifurcated and pivoted to the cranks 24. The rear end of the rod 25 is pivoted to the tube 15 by a horizontal pin 26, disposed, preferably, at a point below the rod or bar 17. The weight of the rod 25 will normally tend to swing the 10 cranks 24 to the vertical position, so that, even if the operator does not grasp the operating lever, the guiding vane or plane 22 will normally be held in the proper inclined position necessary to retain the machine on 15 an even keel when it is moving forwardly. The proper inclination of the plane 22 may be determined by experiment.

A hand wheel 27 is pivoted on a horizontal pin or bolt 28, which extends through the 20 two arms of the bar 16. The periphery of the wheel 27 is grooved and has mounted in it and secured thereto two flexible devices such as wires or ropes 29 which pass around the wheel in opposite directions and pass 25 over two pulleys 30 secured to the horizontal portion of the bar 16. From the pulleys 30 the wires 29 pass into the tube 15 at its upper end and after crossing in the tube pass respectively around two pulleys 31 mounted 30 in the tube 15 on a horizontal pin 32. The two wires 29 then extend rearwardly through a lateral opening 33 in the tube 15 and are respectively secured to opposite ends 35 of a cross bar 34 which is rigidly secured to the lower end of a vertical rock shaft 35, which is pivoted in bearing members 36 secured to bars 37, the forward ends of which are secured to the rear standards 1. A vertical rudder 38 is secured to the rock shaft 40 35. By turning the wheel 27 the rudder 38 may be swung, and simultaneously the guiding plane 22 may be tilted more or less by swinging the lever on the bar 17.

In case the machine in alighting first 45 strikes on the forward carrying wheel 9, the brace rods or bars 14 will sustain the weight of the operator and of the engine 10.

The disposition of the engine and operating parts of the machine is such that the 50 center of gravity will be below the plane 3 and central with respect to the length and width of said plane. In case of the machine falling, this disposition of the center of gravity will cause the planes 2 and 3 to serve 55 as parachutes to retard the velocity of the downward movement.

Owing to the shape and disposition of the planes 2 and 3 and owing to their narrow width, compared with their length, the machine 60 will not be cranky and will not be liable to lateral tipping due to lateral gusts of wind striking them. This arrangement of the planes 2 and 3 will also reduce the

air resistance to the forward movement of the machine.

By locating the propeller 13 adjacent to the rear ends of the planes 2 and 3, the propeller does not disturb the air in advance of the planes, so that the planes constantly ride on fresh undisturbed air, thereby exerting a greater sustaining effect than would otherwise be the case.

By reason of the rod 25 being below the rock shaft 21 the weight of said rod will automatically bring the plane 22 to the proper angle required to keep the machine on even keel during forward movement, so that the operator need not be constantly on guard to keep the machine on even keel.

I do not limit my invention to the structure shown and described, as modifications, within the scope of the appended claims, may be made without departing from the spirit of my invention.

Having thus described my invention, what I claim and desire to secure by Letters Patent, is:—

1. In a flying machine, a frame which includes a supporting aeroplane, a carriage frame of diamond shape having its longest dimension disposed longitudinally and centrally with respect to the longitudinal center of the machine, four carrying wheels 90 rotatively mounted on the carriage frame and disposed respectively adjacent the four 95 corners of the carriage frame, and means for supporting the frame upon said carriage frame.

2. In a flying machine, a frame, an engine supported by the frame, a carriage frame 100 supporting said frame, front and rear carrying wheels rotatively mounted on the carriage frame and disposed respectively fore and aft of the engine, and an upwardly and rearwardly inclined brace secured at its 105 lower end to the carriage frame, and secured at its upper end to the engine.

3. In a flying machine, a frame, an engine supported by the frame, a carriage frame supporting said frame, carrying wheels 110 mounted on the carriage frame, two braces having their forward ends secured to the carriage frame adjacent to the front end thereof and extending upwardly and rearwardly and having their rear ends secured to 115 the engine, an operating lever pivoted to said two braces, and a seat secured to said braces between the lever and engine.

In testimony whereof I have signed my name to this specification in the presence of 120 two subscribing witnesses.

HURSHEL R. COFFMAN.
